UNITED STATES PATENT OFFICE.

MILES OLIVER, OF RUTHVILLE, TENNESSEE.

DESIGN FOR A LINK FOR CLOTHES-LINES.

SPECIFICATION forming part of Design No. 27,699, dated September 28, 1897.

Application filed October 28, 1896. Serial No. 610,366. Term of patent 7 years.

To all whom it may concern:

Be it known that I, MILES OLIVER, a citizen of the United States, residing at Ruthville, in the county of Weakley and State of Tennessee, have invented and produced a certain new and original Design for Pinless Clothes-Lines; and I do declare the following to be a full, clear, and exact description of the invention, such as will enable others skilled in the art to which it appertains to make and use the same.

My invention relates to a design for a link for clothes-lines.

It relates to the entire configuration of the link, and especially to a link constructed of wire.

My invention relates particularly to a clothes-line link as illustrated in the accompanying drawing.

20 The figure illustrates a perspective view of one of the links.

The essential features of my design comprise a length of wire bent to form a straight body portion 1, with end loops 2. These loops project entirely upon one side of the body portion 1, and each consists of the straight member 3 and the curved member 4. The opposite loops lie at right angles to each

other, the right-hand loop being shown in a vertical position, while the left-hand loop is horizontally disposed. Where the loops join the body portion of the link, there are three coils of the wire wrapped about the body portion, as at 5, and the coils at the opposite ends of the link are reversely curved or wrapped. At the inner ends of the coils 5 the terminals 6 of the wire gradually diverge from the body portion 1 to form elongated V-shaped openings 7, the mouths or entrances to which open outward reversely toward the loops. The ends 8 of the terminals 7 lie in the same horizontal plane parallel to the body portion 1.

Having thus described my design, what I claim, and desire to secure by Letters Patent of the United States, is—

The design for a link for pinless clothes-lines, substantially as herein shown and described.

In testimony whereof I hereunto affix my signature in presence of two witnesses.

MILES OLIVER.
